UNITED STATES PATENT OFFICE.

ROBERT D. MORRISON, OF BALTIMORE, MARYLAND, ASSIGNOR OF ONE-HALF TO WILLIAM O. NELSON, OF SAME PLACE.

VEHICLE-TOP.

SPECIFICATION forming part of Letters Patent No. 436,900, dated September 23, 1890.

Application filed February 6, 1890. Serial No. 339,478. (No model.)

To all whom it may concern:

Be it known that I, ROBERT D. MORRISON, of the city of Baltimore, and State of Maryland, have invented a new and useful Improvement in Vehicles, and especially in the arrangements of curtains relating thereto, of which the following is a full description.

The accompanying drawings illustrate the invention, in which—

- 10 Figure 1 is a view of the upper part of the body of a carriage or other vehicle, partly in section, and looking from the front to the rear; Fig. 2, a cross-section of one of the posts; Fig. 3, a perspective view of one of the curtains, showing spring-roller, supplemental roller, and tags attached to the curtain; Figs. 4 and 5, cross-sections of the posts, showing different forms of guides for the curtain; Fig. 6, a side view of a wagon-body with front and back 15 curtain down and middle one half-way; Fig. 7, a view of three posts in section with the curtains in position; Fig. 8, a view of the upper part of one of the posts, showing groove with spring and supplemental roller; Fig. 9, a view of the same with supplemental roller omitted; Figs. 10 and 11, views of tags of different forms used upon the curtains. Fig. 12 shows an end of the supplemental roller or bar.
- 20 The drawings illustrate the body of a vehicle provided at the sides and rear with the usual posts A, which are supported at the base by the rail B, and which extend up to and furnish a support for the top or deck C. The top rail D, which surrounds the deck, is cut out just above where it joins the posts to give room for the bar or roller G to direct the curtain to fall within the grooves in the posts, as will be fully explained.
- 25 Suitably journaled in the upper part of the vehicle are the two rollers F and G. The roller F being of the class known as the "Hartshorn" or "spring" roller, need not be explained; and the roller G, which may as well 30 be a rod, is intended as a guide for the curtain H, wound upon the spring-roller F, and directs it into the grooves in the posts. It is also used as a means for guiding the curtain laterally as well as perpendicularly.
- 35 I will now explain the details of one way by which my invention may be carried out.

Fig. 7 shows top views in section of three posts provided with grooves to receive the edges of the curtain. The grooves should be deep enough to let the curtain enter well into the body of the post, so as to be retained therein during a wind and also to prevent rain from entering. If desired, the curtain-edge may be protected from wear at intervals by a button, clasp, or rivet, as shown at *h h*, 40 Fig. 3. By reference to the figures it will be seen that the center post has two grooves pointing in opposite directions to receive one edge of the curtain running from thence to the next post, while the one to the left in the rear has also a groove at right angles to that which retains the side curtain for the reception of the rear curtain, or, if desired, another post may be used for this purpose. I prefer to make these grooves in a manner to prevent lateral movement of the curtain and hold them in place under any circumstances; and for this purpose I construct the grooves so that they may have a branch at right angles, and provide the edges of the curtains with 45 tags *t*, bent to conform to these branch grooves, as shown in Figs. 2, 4, 5, and 7. These branch grooves may be made in the posts by hand or by machinery, leaving a projection of the wood sufficient to receive a capping-piece *h³*, 50 running the length of the post, which is screwed upon the post after the branch groove *h'* is formed, which leaves the post, when finished, provided with an L-shaped groove; or the groove could be made in the solid post 55 without the capping-piece. The grooves may also be fastened upon the side of the post, if desired, by making suitable metallic pieces in proper shape and securing them to the post, as shown in Fig. 5. A view of the curtain 60 with the tags attached is shown in Fig. 3. The tags should be placed on the curtain in position so that they will not interfere with each other when wound upon the roller. It is evident that a number of forms of tags and 65 grooves may be devised to work equally well—such, for example, as the T-shaped or button-shaped—as shown in Figs. 4, 10, and 11.

As before stated, the roller G may be a simple round rod. I prefer the roller because 70 there would be less friction. Its office is to guide the curtain and hold it plumb over the

groove. It may also have an additional function, that of assisting to retain the curtain in position laterally. I prefer to construct the end of the roller, as shown in Fig. 12, with the concentric projection *g*, and a reference to Fig. 3 will show the position of the tag as it passes over this roller as it is wound or unwound on the spring-roller. The concentric projection *g*, however, is not necessary, as the tag *t* may overlap the end in the same manner and be held securely in place.

The roller *G* may, under some circumstances, be dispensed with; but it is better to have it. In case it is not used I place the spring-roller directly over the groove in the post in position to drop the curtain into the groove, and as the curtain is always in the groove for a short distance, it is possible to operate the device in this way. In such a case I bevel out the upper part of the groove, as shown at *a'*, Fig. 9, and as the bulk of the roller *F* is larger when the curtain is wound than when unwound the roller may be placed in position to conform to an average bulk of the roller and curtain. In the front of the wagon, as shown in Fig. 6, the curtain has but one post and groove. The forward lower end, passing by the dash-board, is properly secured to the lower rail or other suitable part of the wagon.

As an additional preventive to the entrance of rain, a stiffening-piece *i* may be placed within a hem or otherwise attached near the bottom of the curtain, and the curtain below this piece will form a flap hanging over the outside of the lower rail, making the whole water-tight. The usual small glass window may also be put in the curtain, as *W*.

The operation may be seen at a glance. The

curtain is of the ordinary flexible material, impervious to water. It runs up and down in the grooves as directed by hand, may be stopped at any desired point, keeps its position, dispenses with straps and buckles, buttons and button-holes, may be operated in an instant of time, and may be used as sash curtain or blind.

The cross-piece at the lower part of the curtain may be provided with loops and the posts with fastening devices for the loops in case an additional securing device is required to keep the curtain fixed at any point.

What I claim is—

1. In a carriage or wagon body, one or more supporting-posts provided with a groove or grooves running in line with the curtain and having a lateral branch, in combination with a spring-roller, a flexible curtain wound thereon, and a series of rigid tags attached to the curtain at intervals and constructed to conform to the grooves in the post.

2. In a carriage or wagon body, one or more supporting-posts provided with a groove or grooves running in line with the curtain and having a lateral branch, in combination with a spring-roller, a flexible curtain wound thereon, a series of rigid tags attached to the curtain at intervals and constructed to conform to the grooves in the post, and a supplemental roller over which the curtain passes located in position to direct the curtain into the grooves in the posts.

ROBERT D. MORRISON.
